DESIGN FOR A LETTER TRAY OR SIMILAR ARTICLE

Charles E. Jones, Chicago, Ill., assignor to Rockwell-Barnes Company, Chicago, Ill., a corporation of Illinois

Application October 23, 1944, Serial No. 115,926

Term of patent 14 years

(Cl. D74—1)

To all whom it may concern:

Be it known that I, Charles E. Jones, a citizen of the United States, residing at Chicago, in the county of Cook and State of Illinois, have invented a new, original, and ornamental Design for a Letter Tray or Similar Article, of which the following is a specification, reference being had to the accompanying drawing forming a part hereof.

In the drawing:

Fig. 1 is a perspective view of a letter tray or similar article, showing my new design;

Fig. 2 is a plan view of the tray; and

Fig. 3 is an end view of the tray.

I claim:

The ornamental design for a letter tray or similar article, substantially as shown.

CHARLES E. JONES.
